To all whom it may concern:

Be it known that I, Morris Massow, a citizen of the United States, residing in New York city, in the county of New York and State of New York, have invented a new, original, and ornamental Design for a Dress Ensemble, of which the following is a specification, reference being had to the accompanying drawing, forming part thereof.

The characteristic feature of my design resides in the combination on the ensemble disclosed of the specific arrangement of lace inserts around the neckline of the specific V-necked dress and on the sleeves of the bolero jacket as shown.

I claim:

The ornamental design for a dress ensemble, substantially as shown and described.
